United States Patent Office

Des. 178,950
Patented Oct. 16, 1956

178,950

TACKLE BOX OR THE LIKE

Herbert C. Berry, Wonder Lake, Ill.

Application August 2, 1954, Serial No. 31,687

Term of patent 3½ years

(Cl. D58—13)

FIG. 1.

FIG. 2.

FIG. 3.

Figure 1 is a perspective view of a tackle box, or the like, embodying my new design;

I claim:

The ornamental design for a tackle box or the like, as shown.
